(57) **CLAIM**

The ornamental design for a power station, as shown and described.

DESCRIPTION

FIG. 1 is a perspective view of a power station showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof.

FIG. 8 is an enlarged view of the encircled area 8 of FIG. 1;

FIG. 9 is an enlarged view of the encircled area 9 of FIG. 1; FIG. 10 is an enlarged view of the encircled area 10 of FIG. 3;

FIG. 11 is an enlarged view of the encircled area 11 of FIG. 3; and,

FIG. 12 is an enlarged view of the encircled area 12 of FIG. 4.

The broken lines shown in the figures depict portions of the power station that do not form part of the claimed design. In FIGS. 1, 3-4 and 8-12, the dot-dash broken line circles and ovals depict the enlarged view boundaries that do not form part of the claimed design.
